UNITED STATES PATENT OFFICE.

CHARLES A. DRAVO, OF WASHINGTON, DISTRICT OF COLUMBIA, ASSIGNOR OF ONE-HALF TO JAMES G. ANTHONY, OF WASHINGTON, DISTRICT OF COLUMBIA.

DESIGN FOR A BADGE OR ORNAMENT.

52,785.

Specification for Design.

Patented Dec. 24, 1918.

Application filed February 6, 1918. Serial No. 215,709. Term of patent 3½ years.

To all whom it may concern:

Be it known that I, CHARLES A. DRAVO, a citizen of the United States, residing at Washington, District of Columbia, have invented a new, original, and ornamental Design for a Badge or Ornament, of which the following is a specification, reference being had to the accompanying drawing, forming part thereof.

The figure is a view in front elevation of the badge or ornament, showing my new design. The vertical bars are alternate red and white, and the field below the same is blue.

I claim:

The ornamental design for a badge or ornament, as shown.

In testimony whereof I affix my signature.

CHARLES A. DRAVO.
